UNITED STATES PATENT OFFICE

2,645,381

PORTABLE DISPENSING TANK

Charles W. Lattman, Oakland, Calif.

Application March 8, 1948, Serial No. 13,540

1 Claim. (Cl. 222—189)

1

This invention relates to portable containers and more particularly to those designed for the dispensing of liquids such as gasoline. Containers of this general description are usually little more than closed metallic receptacles provided with one or more openings closed by screw-threaded caps for facilitating filling and dispensing of the liquid. In containers of this class which are intended for gasoline a wire mesh strainer is frequently provided in the opening itself or disposed across the mouth of a funnel ordinarily held within the container opening by the screw cap.

Gasoline containers of a well known type include a spout in addition to the filling opening and a more elaborate container of this description includes a hinged cap which is spring actuated to seal the spout aperture but may be manually released to effect dispensing of the liquid.

In the use of containers designed as described for filling portable gasoline stoves, outboard motor tanks, etc. it is frequently very difficult to accomplish the filling operation without spilling gasoline over the receptacle thereby increasing the fire hazard. Also the opening of such receptacles is frequently smaller than the discharge opening of the container thereby making more or less spilling inevitable. Also in filling the gasoline stoves of cabin cruisers and in replenishing the gasoline tanks of outboard motors the filling operation is frequently performed while the craft is rolling or pitching so that the danger of spilling and the attendant fire hazard is aggravated.

To overcome the foregoing and other disadvantages of prior art portable containers I have provided by this invention a container which is safe, efficient and comparatively inexpensive. Therefore, it is a primary object of this invention to provide a portable container of the class described which is pressure-operated as distinguished from the gravity-operated containers commonly employed.

Another object of the invention is to provide a pressure-operated container having a relatively small discharge nozzle, the liquid delivery therethrough being at least equal to the larger, gravity-fed apertures by virtue of the pressure within the tank.

A further object is to provide a pressure-operated container having readily accessible and easily removable closures for facilitating cleaning of the tank and its component parts.

Still another object of the invention is to provide in a pressure-operated container a unique

2

nozzle retention means for preventing the accumulation of dirt and foreign matter therein.

The invention possesses other objects and features of advantage, some of which, with the foregoing, will be set forth in the following description of the preferred form of the drawing accompanying and forming part of the specification. It is to be understood, however, that variations in the showing made by the said drawings and description may be adopted within the scope of the invention as set forth in the claim.

Figure 1 is a sectional view taken vertically through my improved container;

Figure 2 is an enlarged, sectional view of the discharge pipe assembly; and

Figure 3 is an enlarged sectional view of the connection between the flexible hose and the nozzle.

Referring now to Figure 1 the container generally designated 1 includes side walls 2, 3, a top 4, and an inset, conical bottom wall 5, which is preferably welded to the side walls 2, 3, at the marginal portions 6, and centrally provided with a threaded aperture 7 and drain plug 8 therein. Although a cylindrical form of tank is the most economical, it will be understood that the cross-sectional contour of the tank may vary with the requirements of use.

In the top 4 and opposite the drain opening 7 is provided a filling opening 9 with a threaded and flanged reinforcing ring 10 integrally united thereto as by welding. A threaded cap 11 having a peripherally flanged portion and a carrying handle 12 serves to close the opening 9 and seal the same by virtue of lead gasket 13 which is disposed between the opposed flange portions as shown in Figure 1.

A manually operated pump 14 of any suitable design extends through a suitable opening in the top 4 with its outer casing united thereto in any desired fluid-tight manner. The pump handle 15 is conveniently operated from above the top of the container as will be apparent.

A discharge assembly shown generally at 16 includes a cock 17 the body of which is preferably integrally formed to include a lateral mounting plate 18 secured to the top 4 by means of screws 19 extending therethrough and rendered fluid and gas tight by means of the lead gasket 20 disposed therebetween. A centrally apertured projection of the cock 17 extends through an opening 22 provided in the top 4 and threadedly receives a tube 23 of suitable material which is of such length as to almost reach the top of the conical bottom wall 5. The lower end of tube 23

is threaded to receive bushing 24 which also maintains in abutting relationship the T connection 25 having the ingress openings 26 and 27 retaining the centrally apertured screening plugs 28 and 29, respectively. Disks 30 of fine wire mesh may be united to the inner ends of plugs 28 and 29 as by soldering, for example.

It will be observed that the central aperture of cock 17 extends upwardly and laterally and terminates in a threaded opening 31 receiving a 10 similarly threaded fitting 32. The latter in turn has one end externally threaded to receive the terminal bushing 33 of discharge hose 34 which is preferably made of a flexible material which is resistant to the deleterious action of gasoline. To further insure the delivery of only clean gasoline to the nozzle 36 which is suitably connected to the outer end of hose 34, a mesh strainer 35 is interposed between such end 34 and nozzle 36, as shown in Figure 3. A handle 37 conveniently operates the cock to open or closed position as desired.

To the side wall 3 of the container is attached a pair of spaced, offset brackets 39 and 40 integrally united to the wall as by welding at 41 and 42, respectively and constitute a convenient hanger for the hose to encircle in supporting relationship as will be apparent.

A bleeder cock 43 mounted in the top 4 in any suitable manner is provided with an elongated, corrugated extension 44 over which is tightly fitted a short tubular member 45 made of a suitably fabric-reinforced synthetic rubber. Tubular member 45 serves as a retainer for the inserted end of the nozzle 36 when the latter is not in use and prevents the entrance of dirt and other foreign matter therein.

The operation of my improved dispensing tank is as follows. After the tank has been filled through the opening 9 the cap 11 is replaced and screwed down tightly upon the lead gasket 13 through manipulation of handle 12. The pump handle 15 is then operated for a sufficient number of strokes to produce the desired pressure depending of course on whether the tank has been completely filled with gasoline or not. The hose nozzle is then withdrawn from the tubular member 45, the hose 34 uncoiled from about the brackets 39, 40 and the nozzle inserted into the opening of the tank or other receptacle to be filled and the cock handle 37 turned to permit the flow of gasoline. The latter will continue until additional air pressure above the level of gasoline in the tank is required, the resulting condition being easily corrected through further

pumping to the extent desired. The bleeder cock 43 is useful for relieving the air pressure in the tank at any time without emptying the gasoline therefrom as when a period of nonuse is contemplated. It also serves as a means for ready attachment to an air supply such as is found at filling stations when operation of pump 14 then becomes unnecessary.

I claim:

A portable dispensing container for liquid comprising a substantially cylindrical body portion having a top wall and a centrally depressed, threaded-apertured bottom wall, means engageable in said aperture for normally closing said container, means in said top wall forming a filler opening, a filler cap mounted in said opening, a manually operated pump mounted on said top wall and entering said container for a distance whereby the lower end thereof is normally above the liquid level and arranged on actuation thereof to create a pressure on the upper surface of the liquid in the container, said pump being positioned so that substantially all but the handle thereof is disposed within said container, a bleeder cock mounted on said top wall and above the maximum upper level of the liquid, said cock including a resilient extension member having an aperture therein, a delivery cock also mounted on the top wall and having a delivery tube extending downwardly into said tank to a point just above the upper extremity of said bottom wall, a flexible delivery hose connected to said delivery cock externally of said container, a nozzle releasably connected to said hose and having a strainer interposed therebetween, said nozzle being attachable to and detachable from said bleeder cock extension for protecting said nozzle from the ingress of foreign matter when said container is not in use.

CHARLES W. LATTMAN.
